US00D862411S

(12) **United States Design Patent** (10) Patent No.: **US D862,411 S**
(45) Date of Patent: ** Oct. 8, 2019

(54) **SPEAKER**

(71) Applicant: **LG ELECTRONICS INC.**, Seoul
(KR)

(72) Inventors: **Heesu Yang**, Seoul (KR); **Junki Kim**, Seoul (KR); **Gangho Woo**, Seoul (KR)

(73) Assignee: **LG ELECTRONICS INC.**, Seoul
(KR)

(**) Term: **15 Years**

(21) Appl. No.: **35/505,520**

(22) Filed: **Feb. 23, 2018**

(80) **Hague Agreement Data**

Int. Filing Date: **Feb. 23, 2018**

Int. Reg. No.: **DM/100004**

Int. Reg. Date: **Feb. 23, 2018**

Int. Reg. Pub. Date: **Aug. 24, 2018**

(30) **Foreign Application Priority Data**

Aug. 31, 2017 (KR) 30-2017-0040617

(51) **LOC (12) Cl.** **14-01**

(52) **U.S. Cl.**

USPC **D14/204**
